UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

THREAD-CONTROLLING MECHANISM FOR SEWING-MACHINES.

1,135,406.

Specification of Letters Patent. Patented Apr. 13, 1915.

Application filed November 5, 1910. Serial No. 590,917.

To all whom it may concern:

Be it known that I, DUDLEY S. SEYMOUR, a citizen of the United States, residing at Oak Park, in the county of Cook, State of Illinois, have invented certain new and useful Improvements in Thread-Controlling Mechanism for Sewing-Machines, of which the following is a description, reference being had to the accompanying drawing and 10 to the letters and figures of reference marked thereon.

The invention relates to new and useful improvements in sewing machines, and more especially to thread controllers for sewing 15 machines.

An object of the invention is to provide a thread controller which is especially adapted for use in connection with a long arm cylinder machine, wherein the feed is 20 lengthwise of the arm.

The invention consists in the parts and arrangements hereinafter described and set forth in the appended claims.

In the drawings:—Figure 1 is a longitudinal sectional view through the upper portion of the overhanging arm. Fig. 2 is a plan view of the thread controller and its connection to the presser foot lifting mechanism. Fig. 3 shows hand lever for lifting 30 the foot.

The sewing machine to which my invention is applied, is of the long overhanging arm type in which there is a cylindrical bed plate and a feeding mechanism for feeding 35 the material longitudinally of the overhanging arm, and bed plate. The bed plate has been omitted for the sake of clearness and for the further reason that it has no part in the present invention.

40 The usual standard 1 carries an overhanging arm 2 in which is mounted the main shaft 3 operated from a driving pulley 4, in the well known manner. The bar 5 reciprocates in bearings in the forward end of the 45 overhanging arm, and carries at its lower end preferably two needles, one of which is indicated at 6. The needle bar is connected by a link 7 to the crank on the forward end of the main shaft 3.

50 The presser foot 8 is of the usual construction and is mounted at the lower end of a presser bar 9 mounted to reciprocate in the forward end of the overhanging arm. The presser foot is arranged so as to coöperate 55 with the feed 10 that feeds the material,

mounted in a direction longitudinally of the overhanging arm, and underneath the same. The presser bar 9 is a short bar terminating at a point below the crank disk carried by the forward end of the main shaft. A 60 spring 11 is secured at one end by a bolt 12 to the under side of the overhanging arm, and at its free end rests on the top of the presser bar 9. A screw 13 threaded into the under face of the overhanging arm, has 65 its head resting against the spring 11 and serves as a means for increasing the pressure of the spring 11 on the presser bar 9.

The presser bar is lifted by means of a 70 rock shaft 14 which is mounted in suitable bearings in the overhanging arm, and is connected at one end at 15 to a link 16 which in turn is connected at 17 to an arm 18, rigidly fastened to the presser bar. The arm 19 of the rock shaft 14 is connected by 75 a rod 20 to a crank arm 21 carried by a short shaft. This shaft carries in turn an arm 22 indicated in dotted lines in Fig. 1, which arm is adapted to be connected to a suitable treadle.

The rock shaft 14 as clearly shown in Fig. 2, consists of a sleeve which is rigidly attached to the supporting shaft proper, mounted to oscillate in bearings in the overhanging arm. This rock sleeve or shaft 14 85 carries a third arm 23. A thread controller 24 is pivoted at 25 to a bracket attached to the upper face of the overhanging arm and is connected by the link 26 to the arm 23 of the rock shaft 14. The link 26 extends 90 through a slot formed in the upper face of the overhanging arm, and the rock shaft 14 and arms carried thereby, and also the crank arm 21, are each mounted within the overhanging arm. The thread controller 24, is 95 formed in two sections, the outer one of which 27, fits in a recess formed in the face of the inner section and is adjustably secured thereto by a screw 28 passing through a slot 29 formed in the section 27. A thread 100 guide 30 is secured to the outer end of the section 27 by a screw 31. Said thread guide is provided with a plurality of thread eyes as shown in Fig. 2, so that two threads may be separately guided to the needles. A 105 second thread guide 32 is attached to the thread controller 24. A tension device 33 is secured to the overhanging arm, and a tension device is provided for each thread. The thread is led from the supply through 110

the tension devices, then through the guide 32 to the guiding eyes in the thread guide 30. On the upper end of the needle bar are thread guides 34 which reciprocate with the 6 needle bar. The needle threads after passing through the thread guide 30 are led through the thread guides 34 on the needle bar, and thence underneath the guiding lip 35 to the eyes of the needles.

10 The rod 20 is bent so as to extend through the crank arm 21, and the bent end of the rod is extended as shown in Fig. 2, so as to contact with the face of the bearing extending across the overhanging arm. The 15 rod 20 carries a collar 36 and a spring 37 encircling the rod 20 bears at one end against the fixed collar 36 and at its other end against a fixed bracket 38. This spring normally forces the rod 20 so that the crank 20 arm 21 engages the bearing in the overhanging arm and holds the arm 22 in raised position. The arm 19 is provided with an open 25 recess which engages the bent end of the rod 20, as shown in dotted lines in Fig. 1. The spring 37 will hold the rod to the extreme end of its reciprocation and the bent end of the rod free from its seat in the arm 19. This allows the presser foot to vibrate up and down with the arm without putting the 30 same under the strain of lifting the arms 22 and treadle connections. When it is desired to lift the presser foot, the arm 22 is depressed and through the rod 20 and rock shaft 14, the presser foot is raised.

35 As a hand means for lifting the presser foot which is readily accessible to the operator, I have provided the arm 23 with a projection 39. A cam 40 contacts with said projection 39, and is mounted on a short stud 40 carrying a hand lever 41 on its outer end. By the turning of the hand lever, the cam operated thereby, will force the arm 23 in a direction to raise the presser foot.

45 In the operation of my device, the thread controller 24 will be raised and lowered slightly with each feed stroke of the machine, as the feed dog when it is brought into contact with the lower face of the fabric, lifts the presser foot slightly in the 50 well known manner. If the fabric passing underneath the presser foot varies in thickness, it will readily be seen that the thread controller 24 will be raised or lowered in accordance with whether the fabric increases 55 in thickness or decreases in thickness. This raising and lowering of the thread controller is entirely independent of the movements imparted thereto by the movements of the feed dog. In the setting of the stitch, the 60 needle bar as it reaches the upper end of its stroke, draws the thread taut and produces the final pull upon the thread to set the stitch and also pulls thread from the supply. The amount of take-up action of the 65 thread guide 34 on the needle bar will de-

pend upon the position of the thread controller 24. When the fabric increases in thickness, the thread controller 24 will be lowered and a greater amount of thread will be pulled off, while on the other hand, if the 70 fabric decreases in thickness, the presser foot takes a normally lowered position and raises the thread controller 24 so that less thread is pulled off from the supply. I have therefore, provided a means whereby the exact amount of thread required for the formation of the stitch is supplied. I have also provided a very simple thread controller, as the only movable thread eye other than those carried by the thread controller is the 80 thread eye on the needle bar. The thread runs substantially straight the entire length of the overhanging arm, thus avoiding unnecessary tension and wear on the thread.

85 In order to vary the action of the thread controller for any given thickness of material, I may adjust the section 27 of the thread controller so as to lengthen or shorten the thread controller arm. Then again, the thread guide 30 is secured to the end of the 90 arm by a screw 31 and by loosening this screw, the angular position of the thread arm of the thread guide 30 may be varied, thus again varying the effective action of the thread controller.

95 Having thus particularly described my invention, what I claim as new and desire to secure by Letters Patent, is:—

1. The combination of a presser foot, of a rocking member connected to said presser 100 foot for lifting the same, a thread controller mounted on a stationary pivot independently of said rocking member, and a link connecting said thread controller to said rocking member, whereby the movements of the presser foot are imparted to the thread controller and the latter is inactive except during the movement of the presser foot.

2. The combination of a presser foot, a 110 presser bar, a rocking member, a link connecting said rocking member to said presser bar, a thread controller mounted on a stationary pivot and a link connecting said thread controller to said rocking member.

3. The combination of a presser bar, a 115 slack thread controller, means for connecting the slack thread controller to the presser bar whereby the movements of the presser bar are imparted to the slack thread controller, said slack thread controller being 120 formed in sections, means for connecting said sections, said outer section having a thread guide carried thereby.

4. The combination of a presser bar, a 125 pivoted slack thread controller, means for connecting said slack thread controller to the presser bar whereby the movements of the presser bar are imparted to the slack thread controller, a thread guide mounted 130 on the free end of the slack thread con-

troller, and means for permitting the adjustment of the thread guide bodily to and from the pivotal connection of the thread controller.

5. The combination of a presser bar, a pivoted slack thread controller, means for connecting said slack thread controller to the presser bar, whereby the movements of the presser bar are imparted to the slack thread controller, a thread guide mounted on the free end of the slack thread controller, means for permitting adjustment of the thread guide to and from the pivotal connection of the thread controller, and means whereby the angular position of the thread guide may be varied.
6. A sewing machine including in combination, an overhanging arm, a presser bar mounted therein, a rocking member mounted within said overhanging arm and connected to said presser bar, a thread controller mounted on a stationary pivot carried by the upper face of the overhanging arm, and a link for connecting said thread controller to the rocking member.

7. A sewing machine including in combination, an overhanging arm, a needle bar mounted in the overhanging arm, a presser bar mounted in said overhanging arm, a rocking sleeve pivotally mounted within the overhanging arm, a link located in the overhanging arm, and connecting the presser bar to the rock sleeve, a thread controller pivoted on the upper face of the overhanging arm, and extending longitudinally thereof with its free end nearest the needle bar, a link pivoted to the thread controller and to said rock sleeve.

8. A sewing machine including in combination, an overhanging arm, a needle bar, a thread guide carried by the upper end of the needle bar, a tension device mounted on the overhanging arm, a thread controller pivoted to the upper face of the overhanging arm and extending longitudinally thereof, a thread guide carried by the thread controller at a point adjacent the thread guide on the needle bar, and a second thread guide carried by the thread controller at a point

adjacent its pivotal connection, a presser bar, and means for connecting the presser bar with the thread controller.

9. The combination of a presser foot, a rocking member connected to said presser foot, a second rocking member mounted on a stationary pivot, means for connecting said rocking members, whereby a movement of the presser foot will be imparted to both rocking members, and a thread-guiding member carried by said second rocking member.

10. The combination of a presser foot, a rocking member partaking of the movement of said presser foot, a second rocking member mounted on a stationary pivot, and means interposed between the rocking members, whereby the movement imparted to the first named rocking member will be reversed upon the second rocking member, and a thread-guiding member carried by said second rocking member.

11. In a sewing machine, a needle bar, a thread eyelet carried thereby, a rocking frame carried upon the machine frame, means to vibrate said rocking frame, and a plurality of thread eyelets carried by said rocking frame and located at different distances from the pivotal point of said rocking frame.

12. In a sewing machine, a needle bar and means to operate it including a swinging link, a presser bar mounted in a bearing in a horizontal plane below said swinging link, a rocking frame, connections between said presser bar and said rocking frame, a second rocking frame mounted on a stationary pivot and in a horizontal plane above said first rocking frame and connected with said first rocking frame, and a thread-guiding member connected to said second rocking frame.

In testimony whereof I affix my signature, in presence of two witnesses.
